Inventor:
David Freeman

By James Addington, Ames & Seibold
Attys.

UNITED STATES PATENT OFFICE.

DAVID FREEMAN, OF CHICAGO, ILLINOIS.

POOL-BALL RACK.

Application filed May 7, 1921. Serial No. 467,762.

To all whom it may concern:

Be it known that I, DAVID FREEMAN, a subject of the King of Great Britain, residing at Chicago, in the county of Cook and State of Illinois, have invented new and useful Improvements in Pool-Ball Racks, of which the following is a full, clear, concise, and exact description, reference being had to the accompanying drawing, forming a part of this specification.

My invention relates to improvements in pool ball racks and has for its object the production of a device of this character which will be coin controlled, that is, a device which will be locked against use except upon the deposit of a coin of the required denomination.

A further object is the production of a device of a pool ball rack which will be of durable and economical construction and efficient in use.

Other objects will appear hereinafter.

The invention will be best understood by reference to the accompanying drawing, in which—

Fig. 1 is a front elevation of a pool ball rack embodying the invention, portions being broken away to expose underlying parts;

Fig. 2 is a fragmentary top plan view of the construction seen in Fig. 1;

Fig. 3 is a section taken on line 3—3 of Fig. 1;

Fig. 4 is a view similar to Fig. 1 showing a modified form of construction; and

Fig. 5 is a section taken on line 5—5 of Fig. 4.

As illustrated in Figs. 1, 2 and 3, the rack comprises a body 9 in which are provided a plurality of superposed parallel compartments 10 for the pool balls A. The bottom 11 of each compartment is provided at its front edge with an upstanding flange 12 so that the spaces 13 above the flanges 12 will be of a width less than the diameter of the balls so as to prevent the removal of the balls through said spaces 13. Said spaces are provided so as to permit of a view of the balls when arranged in the rack as will be readily understood.

Each compartment 10 is provided at one end with an inlet opening 13 for the passage of the balls in inserting the same into the rack. At the opposite ends of compartments 10 outlet openings 14 are provided for the passage of the balls in being discharged or removed from the rack.

The openings 14 are normally closed so as to prevent the passage of balls therethrough by a closure or door 15 which is hinged at 16, as clearly seen in Fig. 2. The door 15 is normally locked in closed position by means of a bolt 17 which may be operated to release the same only through the medium of a coin controlled mechanism 18. Said mechanism 18 may be of any approved design, the same being provided with a slot 19 for the insertion of a coin of predetermined denomination.

With the construction thus described, it will be seen that after the balls have once been inserted into the rack, the same may not be removed except upon insertion of the proper coin into the slot 19. When this has been done, the coin controlled mechanism 18 will be operated to effect withdrawal of the bolt 17 thereby unlocking the door 15 so as to permit of the same being swung to open position. A suitable handle or knob 20 is provided on the door 15 for manually operating the same.

The bottoms or shelves 11 of the compartments 10 are inclined toward the outlet openings 14 so that the balls will normally accumulate at the right hand end of the rack, in the illustration shown, and upon opening of the door 15, as just described, will move by gravity through the outlet opening 14 and drop into a suitable receptacle 21 provided therefor. This receptacle may be provided with a handle 22 adapted to engage with a hook or support 23 provided on the underside of the rack, as clearly illustrated in Fig. 1.

In the form shown in Figs. 4 and 5, the right hand end of the rack is permanently closed, the flanges 12, however, of the compartments 10 being cut away at the right hand end of the rack to form outlet openings 24 for the balls. In this form the front side of the rack is provided with a door 25 hinged at 26 so as to swing forwardly. The bottoms or shelves 11 of the compartments 10 are, in this form, inclined both laterally and forwardly so that when the door 25 is swung to open position, the balls will roll by gravity down said shelves and be discharged through the openings 24. When thus discharged the balls will drop into a receptacle 21 which will be conveniently arranged to receive the same.

The door 25, as in the case of the door 15, is normally locked in closed position by a

bolt 27 which may be retracted to unlock the door through the medium of a coin controlled mechanism 28 mounted upon the front side of said door. The coin may be 5 inserted into the mechanism 28 through a coin slot 29. A suitable handle or knob 30 is provided for manually opening the door when the same is unlocked. The door 25, in this form, is provided with a glass panel 10 through which the balls in the rack may be viewed.

With a device of the construction set forth, it will be seen that a pool ball rack is provided from which the pool balls may be 15 removed only upon the deposit of the required coin. In the playing of a game, as the balls are knocked into the pockets of the pool table, the same are removed and placed into the rack. Thus after each game, if it 20 is desired to play another game, it will be necessary to deposit a coin into the coin slot of the rack before the balls may again be secured for the purpose.

With this arrangement the services of attendants in pool rooms may be dispensed with or materially reduced and the time which at present is wasted in waiting for an attendant to arrange the balls for use for 25 succeeding games will be eliminated.

While I have illustrated and described the preferred forms of construction for carrying my invention into effect, these are capable of variation and modification without departing from the spirit of the invention. I 30 therefore do not wish to be limited to the precise details of the constructions set forth but desire to avail myself of such variations and modifications as come within the scope of the appended claims.

Having thus described my invention, what I claim as new and desire to secure by Letters Patent is:

1. In a device of the class described, a plurality of superposed compartments for 45 the reception of balls, said compartments having forwardly opening outlets for the passage of balls; the bottoms of said compartments being inclined longitudinally of said compartments to direct the balls toward one end thereof and being forwardly inclined to direct the balls into said outlets; a 50 swingingly mounted door cooperating with all of said compartments for preventing the passage of balls through said openings; coin controlled mechanism for locking said means in operative position; and a re-

ceptacle for the reception of the balls in passing from said compartments upon the opening of said door.

2. In a device of the class described, a 60 plurality of superposed compartments for the reception of balls, said compartments having forwardly opening outlets for the passage of balls, the bottoms of said compartments being inclined longitudinally of 65 said compartments to direct the balls toward one end thereof and being forwardly inclined to direct the balls into said outlets; means for preventing the passage of balls through said outlets; and coin controlled 70 mechanism for locking said means in operative position.

3. In a device of the class described, a 75 plurality of superposed compartments for the reception of balls, said compartments having forwardly opening discharge openings, the bottoms of said compartments being laterally and forwardly inclined to direct the balls arranged in said compartments toward said discharge openings; and means 80 for preventing the discharge of balls through said discharge openings.

4. In a device of the class described, a 85 plurality of superposed compartments for the reception of balls, said compartments having forwardly opening discharge openings, the bottoms of said compartments being laterally and forwardly inclined to direct the balls arranged in said compartments toward said discharge openings; means for preventing the discharge of balls 90 through said discharge openings; and coin controlled mechanism for locking said means in operative position.

5. In combination, a pool ball rack comprising a plurality of shelves for the reception of balls, each shelf being provided with an inlet opening and an outlet opening and having the floor thereof forwardly and longitudinally inclined from the inlet to the 100 outlet openings, a door normally locked closed for closing over the front of the rack, said door obstructing the outlet opening of each shelf to prevent immediate discharge 105 of the balls upon reaching this opening, and coin controlled means on said door for releasing said door upon the deposit of a coin therein.

In witness whereof, I have hereunto subscribed my name.

DAVID FREEMAN.
